ERNEST J. SMITH, OF NEW YORK, N. Y., ASSIGNOR TO R. HOE AND CO., OF NEW YORK, N. Y., A CORPORATION OF NEW YORK.

WEB-FEEDING MECHANISM.

1,324,362.

Specification of Letters Patent.

Patented Dec. 9, 1919.

Application filed January 29, 1916. Serial No. 74,983.

To all whom it may concern:

Be it known that I, ERNEST J. SMITH, a subject of the King of England, residing at New York, county of New York, and State 5 of New York, have invented certain new and useful Improvements in Web-Feeding Mechanism, fully described and represented in the following specification and the accompanying drawings, forming a part of the 10 same.

This invention relates to certain improvements in machines for forwarding material in continuous lengths or webs and has been designed especially for use with rotary web 15 printing machines, and particularly that class of machines known as intaglio printing machines, although the invention has been designed for and may be used with other types of machines.

In rotary web printing machines of that 20 class in which intaglio cylinders are employed, the pressure of the cylinders on the web is very heavy and generally in this class of machines the feed of the web is effected by the printing cylinders while they remain 25 in contact and during the time the machine is running. In certain classes of printing machines, and particularly intaglio machines, the printing cylinders have to be tripped or separated, and when this occurs 30 they cease to feed the web. When this occurs, the whole strain of advancing or forwarding the web falls on the forwarding devices which are employed in this class of 35 machine, and as these forwarding devices, which are generally rolls, are located beyond the printing mechanism, for forwarding the web to the delivery end of the machine, they are at a considerable distance from the paper 40 roll or other source of web supply. In most instances, the period of separation or of non-coöperation of the printing elements is very short, and it is undesirable to stop the whole machine, the forwarding rolls and the rest 45 of the machine continuing to run while the printing elements are in non-printing position. The tension or strain put upon the web from the forwarding or drawing rolls frequently causes breaks in the web and, in 50 any case, even if the web does not break, the continued operation of the rolls results in unnecessary feeding and consequent waste of the web during the time that the printing operation of the printing mechanism is 55 suspended.

It is one object of the present invention

to provide a construction whereby the forwarding or drawing rolls may be silenced and the forwarding of the web stopped when the operation of the printing mechanism is 60 suspended, thus obviating the breaking or wasting of the web.

It is a further object of the present invention to provide a construction in machines where a continuously driven slitter is employed for slitting the web, by which the slitter is driven from the roll driving means 65 and silenced simultaneously with the silencing of the rolls.

With these objects in view, the invention 70 consists in certain novel parts and combinations which will be fully described herein-after in connection with the accompanying drawings, to afford a thorough understanding 75 of the invention.

In the drawings, Figure 1 is a front diagrammatic view, partly broken away, of a printing machine employing cutting, folding and delivering mechanism, with the improved construction for silencing the forwarding rolls applied thereto; Fig. 2 is a front view of the improved construction, certain parts being broken away and partly in section, showing the driving mechanism for operating the part of the machine to 80 which the improved construction is applied, the figure also showing diagrammatically part of a rotary printing couple; Fig. 3 is a sectional view, on an enlarged scale, of the clutch mechanism employed for silencing 85 the rolls, and Fig. 4 is a plan view, partly broken away, showing a part of the driving connections illustrated in Fig. 2.

Referring now to these drawings, the machine chosen to illustrate the invention is a 90 rotary web printing machine in which the form cylinders are arranged for intaglio printing, but it will be understood that the invention is applicable for use with other printing machines in which a web is printed, and may, if desired, be used with machines 95 other than printing machines employed for handling and forwarding webs of material.

In the machine illustrated, the web W is 100 printed upon and forwarded during the printing operation by rotary printing mechanism, one couple being shown, and comprising form and impression cylinders 1, 2, from which it passes under a turning roll 3 to the delivery end of the machine. In the particular construction illustrated, the web is 105 slit by a suitable slitting mechanism, such as 110

rolls 4, 5, and the two parts of the web are passed over a turner bar 6 and are brought together by associating and forwarding devices which in the particular construction 5 illustrated are a pair of forwarding or drawing rolls 8, 9. From these rolls, the associated webs are as usual passed to cutting and folding cylinders 10, 11, and are delivered from a delivery cylinder 12 in the 10 usual manner. The forwarding or drawing rolls are continuously driven during the operation of the machine, and in accordance with the invention means are provided whereby these rolls may be silenced or cease 15 their operation when the printing operation of the machine is suspended and without interrupting the operation of the driving mechanism. While these means may vary somewhat in construction, as illustrated the 20 rolls are driven through a clutch mechanism 13, the particular construction and operation of which may be somewhat varied. Preferably, and as illustrated, one member 14 of this clutch is continuously driven through a 25 train or gearing 15 from the driving shaft 16 of the machine, the other member of the clutch 17 driving one of the rolls, as the roll 8, through intermediate gear 15', roll 9 being driven from the roll 8 in the usual 30 manner, the two members of the clutch 14, 17 having frictional engagement with each other through means of the friction washer 18 located between the members.

The members of the clutch are arranged to 35 slip and thus stop the driving of the forwarding rolls when a predetermined pressure is placed on the web as in the present instance the pressure produced by the cessation of the forwarding web by the printing couples when the printing operation is 40 suspended. In the best constructions means are provided for adjusting the clutch so that it will slip at different degrees of pressure on the web, as, for instance, in the present 45 case when the tension on the web is unduly increased because of the printing cylinders ceasing to coöperate in the feeding of the web. These means may be, as illustrated, an adjusting hand nut 19 on the end of the 50 shaft 20 of the clutch, a compression spring 21 being interposed between the nut and the member 14 and causing it to frictionally engage the other member 17. If desired, the usual antifriction balls may be provided between the clutch members and the fixed parts 55 of the machine on which the clutch members are supported.

In machines embodying a slitter it may 60 also be desirable to silence the slitters when the tension on the web is unduly increased, and in the best constructions means will be provided whereby the slitting rolls may be silenced from the same clutch mechanism as the forwarding or drawing rolls. While the 65 means for accomplishing this may be varied,

in the particular construction shown the clutch member 17 is a gear and the slitting rolls are driven from this member through intermediate gearing 22, whereby the slitting and drawing rolls are simultaneously 70 silenced. It will be understood, however, that if necessary or desired a separate friction clutch may be supplied for the slitter.

While the invention has been illustrated and described in its preferred form, it will 75 be understood that various changes may be made in the form of the clutch and that the invention is not, therefore, to be restricted to the particular form shown, and it is further understood that the invention is intended to 80 be and will be used with printing machines other than intaglio machines, and with machines in which a continuance web is forwarded.

What is claimed is:

1. In a rotary printing machine, the combination with a printing mechanism, the printing members of which act to forward the web when in printing relation, of a pair of web-forwarding rolls located beyond the 90 printing mechanism, means for driving the rolls, and means controlled by the tension on the web for stopping the feeding operation of the rolls without interrupting the driving mechanism when the printing mechanism is not operating on the web. 95

2. In a printing machine, the combination with a printing couple, members of which act to forward the web when in printing relation with each other, of web forwarding 100 rolls, means for continuously driving the rolls, and a clutching mechanism through which the rolls are driven, said clutch mechanism being arranged to unclutch and stop the feeding operation of the rolls when the 105 printing couple is not operating on the web.

3. In a printing machine, the combination with a printing couple, the members of which act to forward the web when in printing 110 relation with each other, of web-forwarding rolls, and a friction clutch for driving the rolls and arranged to slip and stop the feeding operation of the rolls when the printing couple is not operating on the web. 115

4. In a web printing machine, the combination of a printing couple the members of which act to forward the web when in printing relation with each other, web-forwarding rolls, web-slitting mechanism, a friction clutch, and connections from one member of the clutch for driving the rolls and slitter, said clutch being arranged to slip and stop the operation of the rolls and slitter upon a predetermined tension being put upon the 120 web. 125

In testimony whereof, I have hereunto set my hand.

ERNEST J. SMITH.
